ROBOT PHONOGRAPH

Lloyd J. Andres, Chicago, Ill., assignor to: Automatic Instrument Company, Grand Rapids, Mich., a corporation of Michigan

Application March 9, 1936, Serial No. 67,868

13 Claims. (Cl. 274-1)

This invention relates to improvements in robot phonographs, now known as Robophones, and has more particular reference to that type of sound reproducer in which mechanically operated drums are employed to close a number of electric circuits for causing certain actions during the playing of a record, such as lighting lamps, operating machinery, and so on, as distinguished from electrically operated contact 10 means.

These results are accomplished by synchronizing a special repeating phonograph mechanism with contact making means in which electrical contacts are made at frequent intervals. This 15 requires a commutator mechanism which will make several hundred contacts during the time it takes to play a record. In setting up a mechanism for use with a particular record, contacts are located which are engaged at the desired 20 times and corresponding circuits are connected thereto for electrically accomplishing the desired results. If relay operated commutators are used, such as the well-known automatic telephone relays, a large amount of wiring, relays, and other mechanism is required which this 25 invention seeks to avoid and reduce.

The present invention therefore provides more simple means for accomplishing such results requiring less wiring, elimination of operating relays, generally simplifying the construction, and producing a more practical device by the elimination of parts which are likely to get out of order.

Other objects and advantages of the invention 30 will appear in the specification describing an embodiment of the invention, in connection with the accompanying drawings in which,

Fig. 1 is an elevation of the most essential mechanism, some of the parts being broken away, 35 unnecessary parts being omitted, and others being shown in section;

Fig. 2 is a detail section of the drum winding spring as taken on the line 2-2 of Fig. 1;

Fig. 3 is a diagrammatic view and wiring diagram in connection with the section taken on the line 3-3 of Fig. 1;

Fig. 4 is a section taken on the line 4-4 of Fig. 1; and

Fig. 5 is a circuit diagram of certain wiring 50 connections between the drums.

In the present invention the contact maker comprises a double drum mechanism which is connected to the same shaft which drives the phonograph turntable so that it is easily synchronized with a record carried thereon. The 55

specific phonograph mechanism is independent of the present invention but includes certain switches and connections which cooperate with the drum mechanism and contacts.

Referring now more particularly to the drawings, a phonograph mounted on a base 1, has a movable stylus arm 2 with conductors 3 leading therefrom to an amplifier or loud speaker, and various switches and conductors for controlling a motor 4 which drives a vertical shaft 5 extending above and below the base 1. A turntable 6 is fixed on the upper end of the shaft which is rotatable at the desired speed by the motor.

Mounted below the base 1 is a casing 7 for the lower end of shaft 5 and operating mechanism 15 in connection therewith. A pair of commutator drums 8 and 9 having shafts 10 and 11 respectively are fixedly mounted in the bottom of casing 7 and in a spaced frame or supporting plate 20 fixed below the casing.

Projecting through the bottom of the casing 7 is the upper end of shaft 10 of the first commutator 8 which has a spur gear wheel 12 and a clutch member 14 fixed to the gear and together 25 slidably and rotatably mounted on the shaft. A cooperating clutch member 15 is fixedly secured to the shaft to engage with the movable clutch member 14. At the upper end of the hub 12 is a circumferential groove 17 engaged by a yoke 18 to permit relatively free rotation and 30 the yoke is pivotally mounted at one end of a clutch operating lever 19 medially pivoted to a bracket 20 extending upwardly from the bottom of the casing 7.

A spring 21 secured at one end to the clutch 35 side of the lever 19 and at the other end to a post 22 fixed on the bracket holds the clutch members 14 and 15 normally in engagement with each other and the gear 12 meshes with a somewhat wider spur pinion 23 fixed to the 40 turntable shaft 5 so that the gear 12 will continue in engagement with the pinion when the clutch member 14 is moved out of engagement with the clutch member 15.

To disconnect the clutch members a remote 45 control means comprising a relay 24 mounted in the casing 7 attracts the end of the lever 19 when energized, raising the gear 12 and the upper clutch member 14. When the clutch members are connected the commutator drum 8 is 50 rotated synchronously with the record on the turntable.

Arranged in a spiral or helix on the periphery of drum 8 are a plurality of evenly spaced contact lugs or fingers 25 with a similar series 55

of contact lugs on the other drum 9. These lugs successively close a series of switches 26 and 27 at the outer sides of the drums 8 and 9 respectively, insulatingly mounted upon vertical bars 28 extending between the casing 7 and the plate 12. These switches comprise cooperating spring fingers 29 and 30 insulatingly mounted on the vertical bars 28 and normally separated but pressed together to make contact when the corresponding lugs on the drums move in contact with cam projections 31 provided on the inner fingers 30 which ride on the surfaces of the drums.

To rotate the second drum 9 one step at each complete rotation of the cylinder 6, a gear 32 is pinned to the lower end of shaft 10 which meshes with the pinion 33 fixed to a shaft 34 carried by the lower plate 12. Also fixed to the shaft 34 is a flanged member 35 having a Geneva movement drive pin 36 and a locking cam 37 which cooperate with a Geneva wheel 38 fixed to the shaft 11 of the other commutator drum 8. The drum 9 is therefore rotated from one lug or contact 25 to the next one to close the succeeding switch 27 while the drum 8 is moving to open the last of its series of switches 26 and to again close the first switch of its series.

Connected at one end to the lower clutch member 15 which is fixed to the shaft 10 is a spiral spring 39 and the other end of the spring is anchored to a post 40 fixed in the casing 7. The spring is wound to increase its tension as the first contact drum 8 is driven by the pinion connected to the turntable. The Geneva mechanism is reversible and to reset the commutator drums to starting position the outer end of the lever 19 is depressed manually or by energizing the relay 24. This releases the clutch connection between the members 14 and 15 and permits the spring 39 to unwind and rotate the contact drums reversely to starting position. To retard the counter-rotation of the first drum 8 a spring pressed pawl 41 engages teeth of a ratchet gear 42 to provide an escapement and a pawl 43 mounted on the lower plate 12 engages a stop 44 in connection with the second drum 9 when it is returned and reaches its starting position.

A simple multiple contact construction is thus provided; no operating wiring or relays are required and to connect the control circuits which are to be used it is only necessary to connect the corresponding switches of the two drums to prepare for a particular record.

The necessary wiring for connecting any number of these devices for operation by the contacts of the drums 8 and 9 is extremely simple as will be apparent by reference to the schematic circuit diagram as shown in Fig. 4. The two contact drums are represented by commutators 8^a and 9^a respectively; the contact fingers 30 which are joined together in each of the series are represented by contact arms 30^a and 30^b; and the open contacts 29 are represented by the circles of contact points 8^b and 9^b.

A source of current supply represented by a battery 45 is connected between the joined inner contact fingers 30^a and 30^b. In actual practice, connections are made only to the contacts 30 it is desired to use but for the sake of illustration a bank of twenty contacts or switches 26 is illustrated. One wire is connected to each one of the switch contacts 8^a of which a group 46 only is indicated; and a similar bank of conductors 47 is connected to the second series of drum contacts 9^b. With contacts closed at both number 75 one contacts of each drum, a number one con-

trol circuit is made up by connecting across the corresponding number one contact wires 46 and 47. A circuit will then be closed from the battery to the number one switch of the drum 8^b, corresponding wire 46 through the number one control circuit to the wire 47 and number one contact of the second drum 9^b and thence back to the battery.

If there are twenty control circuits on each drum the first twenty control circuits are made available by connecting the circuits between each of the wires 46 to the number one wire 47; the circuits 21-40 by connecting across from each of the wires 46 to the number two wire 47; the circuits 41-60 by connecting each of the remaining open contacts of the switches 26 to the second switch 27, and so on, making four hundred available control circuits with twenty contacts on each drum. If a greater number of control circuits are desired the number of contacts on each drum may be increased or the number of drums may be increased and similarly operated.

In operation with the parts in normal position, the turntable 6 is put into operation to play a record and the first drum 8 is continuously rotated in synchronized relation with the playing of the record to close its series of switches in progressive relation. At each complete rotation of the first drum the second drum is partially rotated to close a succeeding switch of its series. During the second actuation of the first series of switches on the drum 8 the second switch of the second series of the drum 9 is closed. At the third actuation, the third switch of the second drum is closed; and so on until each switch of the first series has been closed in relation with each switch of the second series.

As the operation of a different control circuit is thus possible at each closing of the switches in the first series the control circuits may be operated at a large number of closely spaced intervals during the playing of a record. A great amount of wiring is thus eliminated. The only fixed wiring is the connections between the jointed contacts of the two series of switches and the battery; and the circuits actually used are merely connected between the open contacts of the corresponding switches to the device which is to be operated at that time.

When the clutch operating lever 19 is moved either manually or by the relay 24 to release the clutch elements 14 and 15 the spring 39 returns the drums to their original or starting position and the operation of the record may be repeated either by closing a switch each time the record is to be played or by automatically repeating the phonograph operation. A simple circuit arrangement for carrying out this operation is shown more clearly in Fig. 3.

In the type of phonograph illustrated in Figs. 1 and 3 there is a motor 4 for driving the turntable and a motor 50 mounted below the arm 2 having a driven shaft 59 operating a gearing for actuating the pick-up arm 2 to and from operating position as it passes over the record. The specific structure of this pick-up arm drive is not essential to an understanding of the invention, a particular form of such a drive being shown in my co-pending application for Record repeater, Serial No. 89,049, filed July 6, 1936, but the necessary cooperating elements and their operation is shown and described in connection with Figures 1 and 3 as herein described. These motors receive current from a source of power through current

mains 51 and 52 and a main switch 53. The motor 50 receives current from the main 51 through conductors 54 and by way of a divided circuit comprising a conductor 55 in which is a momentary or continuous operation switch 56 and conductors 57 in which there is a switch 58 actuated by a periodic shaft 59 on the pick-up arm carriage which makes one complete turn for each movement up the pick-up arm as driven by the motor M. This shaft carries a cam 60 having a flat or dwell portion 61 engaged by a spring contact member 62 which closes the switch 58 when the spring finger 62 rides on the circular portion of the cam but allows the switch to open when the spring finger rests on the flat or dwell portion 61. This divided circuit containing the two switches 56 and 58 is connected to the opposite main 52 by a conductor 63 through a mercury limit switch 64 which is a part of the cut-off mechanism closed in one limiting position to make a connection to the motor 50. Also connected in parallel with the motor 50 by conductors 65 and 66 is the relay 24 which operates the clutch lever 19. Shown in connection with the clutch lever 19 is a contact switch 70 having a spring contact member 71 moved by the lever 19 to open the switch when the relay 24 is energized. The terminals of this switch are shown connected by conductors 72 and 73 to one side of the battery 45 and to one of the switches 27 while the other side of the battery is connected to one of the other switches 26 by a conductor 74. The opening of this switch 70 therefore prevents the supply of current from the battery to any of the circuits closed by the drums 8 and 9 and therefore prevents the establishment of circuits through the drum contacts when the drums are being restored by the spring 39 to their original or starting position. In operation the turntable motor 4 is first started, the pick-up arm motor 50 actuates the pick-up arm 2 to engage a record on the turntable and as soon as the pick-up arm is in place this motor is stopped until it is desired to again operate the pick-up arm, lifting it from the record and returning to starting position. It is at this time that the relay 24 is actuated, releasing the clutch 14-15 and allowing the drums 8 and 9 to return to their starting position.

Assuming the parts diagrammatically shown in Fig. 3 to be in the ordinary position of rest and ready to start the phonograph, the switch 64 and ready to start the phonograph, the switch 64 being closed, the closing of the main switch 53 will start the phonograph motor 4 in operation and the pick-up arm motor 50 is started by momentarily depressing the switch 56 which will close the circuit through the motor 50 from the main 51 through conductors 54, 55, switch 56, conductors 63 and switch 64 to the other main 52. The starting of this motor will operate the shaft 30 until the high portion of the cam 60 moves the spring contact 62 to close the switch 58 whereupon the switch 56 may be released if only a single operation of the record on the turntable is desired. At this time the relay 24 receives current from the main 51 through conductors 54, 65, 66, 57, 63, and switch 64 to the other main 52 and the clutch 19 is operated to open the clutch mechanism.

When the limit switch 64 is engaged at or near the end of playing the record it closes a circuit through the switch 58 to the motor 50 for operating the pick-up arm and energizing the magnet

24 to restore the drums 8 and 9 to their starting points as above explained.

If it is desired to continuously repeat the same record the switch 56 is permanently closed so that after the cycle of operations is completed for playing the record, which would ordinarily bring the cam 60 to the position as shown in Fig. 3, in which case the switch 58 would be open, another energizing circuit is closed through the motor and through the switch 56 by way of conductors 54, 55, 63 and limit switch 64, which restarts the motor 50 and repeats the operation automatically as long as the switch 56 remains closed.

With this construction it will be seen that the record may be played once or repeated, and that the contact drums are automatically operated in synchronism with the mechanism and returned to their starting position each time the playing of a record is completed, and that while the drums are being returned to their starting position the energizing circuit for the drum contacts is opened.

I claim:

1. In a multiple contactor for a robot phonograph having a turntable for playing a record, a commutator geared to the turntable to make a plurality of revolutions during the playing of the record, a second commutator, and mechanical means actuated by the first commutator having circuits dependent upon the first commutator for partially rotating the second commutator at each revolution of the first commutator.

2. In a multiple contactor for a robot phonograph having a turntable for playing a record, a rotary commutator geared to the turntable to rotate therewith, and a second commutator driven intermittently by the first commutator to connect the first commutator electrically to a different series of control circuits at each revolution thereof so that events may be caused to occur at any one of a plurality of closely spaced intervals during the playing of a record by interconnections between the commutators.

3. In a multiple contactor for a robot phonograph having a turntable for playing a record, a commutator geared to the turntable to make a plurality of revolutions during the playing of a record, a second commutator for closing circuits depending also upon the first commutator, and a Geneva movement driving connection between the commutators so that the second commutator is rotated one space at each revolution of the first commutator.

4. In a multiple contactor for a robot phonograph having a turntable for playing a record, a commutator driven by the turntable to make a plurality of revolutions during the playing of a record, a second commutator, a Geneva movement gearing connecting the commutators so that the second commutator is rotated to make a new contact at each revolution of the first commutator, a clock spring tensioned by the rotation of the first commutator, a pawl for stopping counter-movement of the second commutator at the starting position, and means for disconnecting the first commutator from the turntable to allow the spring to rotate the commutators back to the starting position.

5. In a multiple contactor for a robot phonograph, a turntable having a pinion, a commutator, a gear meshing with the pinion, a clutch for connecting the commutator to the gear, a torque spring connected to the commutator, and means for stopping the return movement of the

- commutator under the action of the spring when the clutch is released so that the commutator will thereby be returned to its starting position and thus reset for the next playing of the record.
5. 6. A multiple contactor comprising two commutators, a series of switches related with each commutator, a source of electrical energy, one side of each series of switches being joined and connected together through said source, and 10 means for partially actuating the second commutator to close a new switch thereof in series with a circuit including said source of energy and a switch of the first commutator at each complete actuation of the first commutator.
15. 7. In a multiple contactor, the combination of two rotatably mounted drums, a series of switches related with each drum so that the switches of each series are closed successively by rotating the corresponding drum, and means for rotating one 20 drum, the other drum being partially rotated progressively by the one drum and the switches of both drums determining the circuits closed.
8. The combination of a pair of cylinders each having a helically arranged series of contact lugs, 25 a row of switch members arranged longitudinally along each cylinder so that the switches in each row are closed successively by the lugs of their related cylinders, a plurality of control circuits, one side of said switches being connected together and through a source of electrical energy, and said circuits being connected between the open sides of the two rows of switches, and means for partially rotating one cylinder progressively in relation to the rotation of the other cylinder.
30. 9. In a multiple contactor for a robot phonograph having a turntable for playing a record, commutating means for successively energizing a plurality of control circuits in coordination with the playing of the record, said means comprising a pair of rotary commutators each having a plurality of spaced contact fingers, the first commutator being driven continuously through a plurality of revolutions during the playing of the record, and the second commutator being intermittently rotated by the first commutator to 35 make one new contact at each revolution of the first commutator to afford connection being made from the contacts of the first commutator to a different series of control circuits at each revolution of the first commutator.
10. In a multiple contactor for a robot phonograph having a turntable for playing a record, a rotary commutator having a plurality of spaced contacts for energizing controlled circuits in co-ordination with the playing of the record, the commutator being geared to the turntable; and a second commutator also having a plurality of spaced contacts and driven through an arc corresponding to the spaces between the contacts 5 at each complete revolution of the first commutator to afford connections from the first commutator contacts to a different series of circuits at each revolution thereof so that actions may be thereby initiated at any one of a plurality of 10 closely spaced intervals during the playing of a record.
11. In a multiple contactor for a robot phonograph having a turntable for playing a record, a commutator, a clutch for connecting the commutator to rotate with the turntable, a second commutator, an intermittent gearing connecting the commutators so that the second commutator is rotated to make a new contact at each rotation of the first commutator, means for returning 15 the commutators to an initial starting position corresponding with the starting position of the record, and means to release the clutch when the record is played to enable the spring to return the drums to their starting position.
12. In a multiple contactor for a robot phonograph having a turntable for playing a record, a pick-up arm and a motor for moving it to and from record engaging position, a plurality of 20 commutators driven by the turntable, each having a series of contacts, intermittent gearing connecting the commutators, a clutch for connecting the commutators to the turntable, and a relay actuated when the pick-up arm motor is actuated to release the clutch, and means for returning 25 the commutators to initial position when the relay is actuated.
13. The combination in a multiple contactor for a robot phonograph having a turntable for playing a record, of a rotary commutator geared 30 to the turntable to rotate therewith, a second commutator driven intermittently by the first commutator to connect the first commutator to a different series of control circuits at each rotation thereof, a source of current supply connected between the contacts of the commutators and including a separately operable switch, a clutch mechanism for releasing the connection of the first commutator to the turntable including an operating lever which controls the said separate switch, and a relay for actuating the lever to release the clutch and open the said switch when the relay is energized.

LLOYD J. ANDRES.
